UNITED STATES PATENT OFFICE.

MARSHALL L. SHEPHERD, OF MONTGOMERY, ALABAMA, ASSIGNOR TO SHEPHERD AUTOMATIC SWITCH CO., OF MONTGOMERY, ALABAMA, A CORPORATION.

RAILWAY-SWITCH MECHANISM.

1,070,193.

Specification of Letters Patent.

Patented Aug. 12, 1913.

Application filed September 28, 1911. Serial No. 651,738.

To all whom it may concern:

Be it known that I, MARSHALL L. SHEPHERD, a citizen of the United States, residing at Montgomery, in the county of Montgomery and State of Alabama, have invented new and useful Improvements in Railway-Switch Mechanism, of which the following is a specification.

This invention relates to railway switch mechanism for controlling the passage of rolling stock from a main track to a branch track or siding, and vice versa.

The primary object of the invention is to provide a positive and reliable type of switch mechanism adapted to be automatically operated by the rolling stock and locked and guarded in normal or switch-closing position against surreptitious or accidental adjustment.

A further object of the invention is to provide a switch mechanism which is adapted to be automatically operated by the rolling stock from either the main or branch line and to lock the open switch rails against accidental closing and insure their positive control by the rolling stock until the latter has passed from one track to the other.

A still further object of the invention is to provide a switch mechanism which will positively close after actuation and the passage of a train from one track to the other and lock the switch rails in normal or closed position so as to obviate the liability of accidents to following trains, while permitting through trains on the main line to travel over the switch point at high speed without liability of deranging the switch mechanism.

A still further object of the invention is to provide a switch mechanism which cannot be left open, which obviates the well known objections to switches of the kind in common use, which is operable automatically by means under control of the driver or engineer of a car or locomotive and may also be operated in an authorized manner by hand when occasion requires and in conjunction with a suitable switch stand and signal, and which affords a maximum safeguard against accidents to the traveling public.

With these and other objects in view, the invention consists of the features of construction, combination and arrangement of parts, hereinafter fully described and

claimed, reference being had to the accompanying drawings, in which:

Figure 1 is a top plan view of the rails and switch mechanism at a switch point, showing the switch rails locked in normal position for travel on the main line. Fig. 2 is a similar view, showing the switch rails adjusted and locked in open position for travel between the main and branch lines. Fig. 3 is a view similar to Fig. 2, showing the switch rails unlocked for retraction upon the release of the guard rail by the wheel flanges of the rolling stock. Fig. 4 is a longitudinal section on line 4—4 of Fig. 1, showing the revolute switch throwing member in side elevation, and illustrating the action of the switch actuating device on the car or locomotive in full and dotted lines. Fig. 5 is a vertical longitudinal section on line 5—5 of Fig. 1, showing the switch throwing member in side elevation and in normal position. Fig. 6 is a vertical transverse section on line 6—6 of Fig. 1, showing the switch actuating device in engagement with the cam groove of the switch throwing member. Fig. 7 is a top plan view of the trip device and its controlling means. Figs. 8, 9, 10 and 11 are enlarged detail transverse sections on the line 8—8 of Fig. 2, showing the different positions of adjustment of the shifting devices. Fig. 12 is a transverse section on line 12—12 of Fig. 1, illustrating the construction of the secondary trip member of the branch track portion of the switch mechanism. Figs. 13 and 14 are detail sections on line 13—13 of Fig. 1, showing the guard rail in its normal and shifted positions. Fig. 15 is a detail view of the slip-joint or lost-motion connection between one of the switch rails and the shifting levers operated by the guard rail. Fig. 16 is a transverse section on the line 16—16 of Fig. 1. Fig. 17 is a detail plan view of the locking dog or latch and co-operating parts of the switch mechanism, showing the dog in normal position to hold the switch rails closed. Fig. 18 is a similar view, showing the dog in position to hold the switch rails open. Figs. 19, 20 and 21 are diagrammatic views, illustrating the operation of the revolute switch throwing device and the switch actuating device on the car or locomotive.

Referring to the drawings, 1 and 2 designate the main line rails, 3 and 4 the branch

line or siding rails, and 5 and 6 the switch rails connected for movement in unison by the rod 7, said rails 5 and 6 forming a switch movable laterally to open and close communication between the main and branch line. These parts of the switch system may be of any approved construction.

Arranged between the tracks of the main line, in the main line approach to the switch, 10 is a casing 8 bolted or otherwise firmly secured to the ties and having a longitudinal slot 8^a at one side, and in which is revolubly mounted a drum or roller 9, forming a switch throwing member. This drum or 15 roller is provided with a spiral groove 10 to receive the laterally bent lower end of a switch actuating or trip device 11, comprising an arm or lever pivotally mounted intermediate of its length on the axle 12 of the 20 truck of a car or locomotive. On said laterally bent lower end of the arm or lever 11 are friction rollers 13 to travel in the slot and groove and run along a track surface 14 integral with and arranged at one side of 25 the casing. The lever is adapted to be normally held elevated and inoperative by a pivoted latch or detent 15, normally held in lever engaging position by a spring 16 and adapted to be tripped by the engineer or 30 driver through the medium of a cord 17, whereby the lever may be released and allowed to drop by gravity when the train approaches the switch and it is desired to throw the switch to permit the train to pass 35 from the main to the branch line. The groove 10 opens at its proximal and distal ends 18 and 19 horizontally through one side of the drum, and such ends thence curve spirally and communicate at an intermediate point in the base of the drum. The 40 construction is thus such that the actuating device in traveling through the portion 19 will return the drum to normal position, thereby resetting it for subsequent operation. 45 Channeled or grooved guide rails 20 and 21 are provided to respectively guide the rollers to the slot and groove and elevate the actuating device, after the drum has been turned to its normal position, in which it is again 50 engaged and held by the detent 15. Arranged parallel with the slotted side of the casing is a vertical flange or plate 22 forming a guideway 23 for the travel of the actuating device and a guard to prevent the introduction of a tool in an attempt to tamper 55 with the drum or throw the switch. Hence the drum can only be turned by a proper type of actuating device under the power of the locomotive or car on which it is mounted. 60 Projecting forwardly from the drum is a shaft 24 suitably journaled and carrying a cam or crank arm 25 and a holding and releasing lug 26, which elements may be adjustably mounted on the shaft so as to be 65 properly positioned for action when the

switch point is arranged either for controlling a branch line at the right or left of the main line; in other words, to adapt the switch throwing device for either right or left hand use. The cam 25 is movable in a cam loop or strap 27 at one end of a switch shifting bar 28 formed of sections 29 and 30, respectively fixed to the loop 27 and pivoted to the switch rail 5, said sections being coupled by a slip-joint or lost-motion member 31, herein shown in the form of a slotted bar or link. This member 31 is adapted to permit the sections 29 and 30 to have certain movements independent of each other, as hereinafter described. The loop 27 is provided with cam faces 32 and 33 adapted to be engaged by the cam 25 to slide the loop outward and inward on a suitable antifriction roller or support 34, between which surfaces said cam is movable to have a certain amount of lost motion without adjusting the loop.

The bar section 30 is provided with a pair of spaced keeper notches or recesses 35 and 36, adapted to be engaged by a projection upon one of the arms of a bell-crank locking device or lever 37, normally held in locking position by a spring 38. To the other arm of this locking lever is attached a rod 39 having a hooked end 40 to engage the lug 26 whereby the locking device is adapted to be tripped into and out of locking position. A spring 41 is arranged to press the switch rail 5 normally into contact with the rail 3 to normally hold the switch point closed for continuous travel over the main line and is of sufficient strength to return the parts of the switch mechanism controlled thereby to normal or closed position after actuation and release.

It will be observed that the construction and arrangement of the parts thus far described is such that on the preliminary travel of the actuating device 11 in the portion 18 of the spiral groove 10 the cam 25 will be turned from its normal position until it contacts with the cam surface 32, during which it will travel for its lost motion period without transmitting motion to the loop 27. During such period, however, the lug 26 will be turned to draw upon the rod 39 and thereby effect the retraction of the latch 37, which will move out of engagement with the recess 35, thus freeing the switch point for adjustment, the hook of the rod 29 being maintained during such period of motion in engagement with the tooth of the lug. The lost motion period of turning movement of the cam 25 ensues during a portion of the preliminary travel of the actuating device in the groove portion 18, and during the remainder of such travel of said actuating device in said groove portion the cam is turned until it has been given a complete quarter revolution, during which

it engages the surface 32 and slides the loop 27 outward, thus taking up the lost play in the connection 31 and adjusting the bar 28 until the switch point is fully opened and 5 the locking device 37 comes opposite and snaps into the keeper recess 36, thus locking the switch in open position for travel from the main line to the branch line. On its final travel in the portion 19 of the groove 10, the actuating device returns the drum and cam 25 to normal position, and the cam engages the surface 33 and slides the loop 27 and bar section 29 back to normal position without disturbing the bar section 30 15 or releasing the switch, which thus remains locked in open position. When the loop 27 is slid outward the rod 39 is released from engagement with the lug 26, but upon the return of said loop to its normal position 20 the bar again engages the lug, the above described operation of the parts being clearly illustrated in Figs. 8 to 11, inclusive, of the drawings.

Arranged in the branch line alongside the 25 rail 3 is a laterally sliding bar or rail 42 forming a combined guard rail and switch actuating device. This rail 42 is adapted to be engaged and slid inwardly by the flanges of the wheels of the rolling stock 30 traveling along the rail 3 and is supported by crank arms 43 from a longitudinally extending rock shaft 44. Said rail 42 is connected by a link 45, slideable through the rail 3, with the outer arm of one of the 35 levers of a pair of laterally swinging transmission levers 46 and 47 pivotally connected at their inner ends, as at 48, and arranged in longitudinal alinement when the switch point is closed. The outer arm of the other 40 lever 47 is coupled by a slip-joint or lost-motion connection with the section 30 of the shifting bar 28, said connection comprising a rod 49 rail 5 or bar section 30 and slideable through the rail 3 having a 45 hooked inner end pivotally engaging the rail 5 or bar section 30 and a threaded outer end engaging the internally threaded end of a sleeve 50, in which is fitted to slide the inner end of a rod 51 pivotally coupled to 50 the lever 47, the construction of which connection is clearly shown in Fig. 15. The inner ends of the rods 49 and 51 are normally spaced apart so that when the rail 42 is shifted inwardly and the inner ends 55 of the levers 46 and 47 swung outwardly, as shown in Fig. 4, a part of the transmission motion of the rail and levers will be taken up in sliding the rod 51 into engagement with the rod 49, and the remainder of such 60 movement taken up when the rail 3 is thus primed for shifting movement by the taking up of the lost motion to shift the switch rails to open position. Extending longitudinally between the rails 5 and 6 is a rock 65 shaft 52 having crank arms 53 engaged by

the slotted inner ends of vertically swinging levers 54 extending transversely beneath the rail 5 and fulcrumed to the ties or other suitable supports. Said rock shaft is also provided with a crank arm 55 operative to 70 engage and release the latch or locking device 37. The levers 54 are slotted at their outer ends to receive pins or projections upon the lower ends of vertically movable primary and secondary trip devices or bars 75 56 and 57 movable in guides 58 and held normally elevated by springs 59. These trip devices 56 and 57 are arranged adjacent to and beyond the respective ends of the rail 42 in the branch line and are adapted to be depressed by the flanges of the wheels traveling over the rail 3 to impart an actuating motion to the shaft 52, whereby the arm 55 is rocked to release the latch or locking device 37. 80

The operation of the switch throwing device in the main line has been hereinbefore described, and it will be seen that the lost-motion connections permit actuation of the same and the shifting of the switch point 90 to open position thereby without communicating motion to the rail 42 and the parts controlled thereby. When the switch point is thrown in the manner set forth to open position for the passage of a train from the main line to the branch line, the switch point remains locked in such position by the engagement of the latch 37 with the recess 35 until the train passes from the main tracks or to the branch line tracks and the wheels 95 of the train engage and depress the trip 56. This rocks the shaft 52 and releases the latch 37 for the subsequent automatic closing movement of the switch, but as the wheels of the train at the same time engage and slide the bar 42 inward the shifting bar section 30 is held from inward movement and the switch point held positively open until the train is fully on the branch track and the last wheel of the train has passed beyond the distal end of the bar or rail 42, when the switch point is automatically closed and the parts positively returned to normal position by the action of the spring 100 41. When a train approaches the switch point from the branch line for passage onto the main line, the first wheel of the train engaging and depressing the trip 57 releases the latch 37, thus freeing the bar section 30 for movement, so that when the wheel shifts the rail 42 inward motion will be transmitted to the levers 46 and 47 to open the switch point, in which position it is locked by the engagement of the latch 37 with the recess 35, in the manner before described. 105 The switch point is thus held open until the last wheel of the train passes onto the main track, thus insuring the safe passage of the train from the branch to the main line. In the travel of the train the first wheel engag- 110

ing and depressing the trip 56 releases the latch, but the switch point is held open by the wheels of the train which hold the rail 42 pressed inward until the last wheel passes 5 beyond the switch point onto the main tracks, when the parts are released and the switch mechanism automatically reset and the switch point positively closed.

From the foregoing description, taken in 10 connection with the accompanying drawings, the construction and mode of operation of my improved switch mechanism will be readily understood, and it will be seen that the invention provides a switch mechanism which is adapted to be automatically operated from either the main or branch line for the passage of rolling stock in either direction from one line to the other; and that the switch cannot remain open after 20 passage of a train, but will positively close and remain closed until again actuated, so as to prevent accidents to following trains and thus safeguard the traveling public. It will be further seen that the switch throwing 25 devices in the main and branch tracks are adapted to operate independently of one another and control a common locking means, whereby the construction is simplified and friction reduced owing to the minimum number of parts operating at a time.

The invention overcomes the well known objections to split and other common types of switches in use, inasmuch as a safe crossing is insured at all times. 30 It will be understood, of course, that the motion transmitting parts of the switch mechanism will be suitably housed and protected from the elements and accidental injury, as well as from damage or operation 40 of the switch by malicious persons or intending train wreckers, the construction being such that the switch can only be thrown under ordinary conditions by the power of passing rolling stock. It is desirable to 45 adapt the switch to be thrown at times by manual operation, to which end the parts may be arranged to be operated from an ordinary switch stand and signal, or one of any suitable construction.

50 Having thus described the invention, what I claim as new is:

1. In a railway switch, a self-closing switch point, a self-projected locking device for locking the switch point in open 55 and closed positions, means operative in the passage of a train from the main line to the branch line for successively retracting the locking device, throwing the switch and releasing the locking device to lock the switch 60 in thrown position, and means operative in the passage of a train from the branch line to the main line for successively retracting the locking device, throwing the switch and holding the switch open until the train 65 passes into the main line, and finally releas-

ing the switch to permit said switch to automatically close and to be locked in closed position, said latter named means being operative in the travel of a train from the main to the branch line to retract the locking device and hold the switch open until the train has fully entered the branch line and to finally release the switch for an automatic closing action.

2. In a railway switch mechanism, a 75 switch throwing device comprising a casing having a longitudinal guide slot at one side thereof, a guard disposed in parallel relation to the slotted side of the casing and forming a passage communicating with said slot, and a revolute switch throwing member arranged within the casing and having a longitudinal spiral groove adapted for engagement with a traveling operating element, said groove having portions arranged to first effect the movement of said switch throwing member to switch throwing position, and then to return said switch throwing member to normal position.

3. In a railway switch, an automatically closing switch point, a switch bar composed of sections having a lost motion connection, one of said sections being connected with the switch point, a yoke connected with the other switch bar section and having oppositely disposed engaging surfaces, a latch device adapted to engage the first named switch bar section to lock the same against movement, a revolute switch throwing device, a crank carried thereby and normally disposed between said surfaces of the yoke, whereby through opposite movements of said switch throwing device the yoke is adapted to be moved in opposite directions, 100 said crank having a lost motion movement prior to engagement with the surface of the yoke to throw the switch bar, a lug movable with said crank, and a latch releasing member adapted to be actuated by 105 said lug on the lost motion movement of the crank.

4. In a railway switch, an automatically closing switch point, a switch bar connected therewith, a locking device for holding the switch bar in switch opening and closing positions, operating devices in the main and branch lines, motion transmitting elements coupled to the respective operating devices and each having a lost-motion connection 115 with the switch bar, a lock releasing device controlled by the operating device in the main line, said lock releasing device being actuatable by said operating device prior to the actuation by the latter of the associated motion transmitting element, a lock releasing device in the branch line, and spaced train-controlled devices in the branch line for actuating said lock releasing device.

5. In a railway switch, a self-closing 130

- switch point, a self-projected locking device for locking the switch point in open and closed positions, a train-controlled device in the main line for unlocking and 5 throwing the switch, a laterally movable, wheel-operated guard rail in the branch line operative on actuation to throw the switch upon the passage of a train from the branch line to the main line and to hold the switch open upon the passage of a train from the main line to the branch line, and train-controlled means in the branch line for unlocking the switch when the train approaches or leaves the main line.
- 10 6. In a railway switch, an automatically closing switch point, a switch bar connected therewith, a locking device for holding the switch bar in switch opening and closing positions, a revolute operating device in the main line, a laterally movable operating device in the branch line, motion transmitting elements coupled to the respective operating devices and each having a lost motion connection with the switch bar, a lock 15 releasing device controlled by the operating device in the main line actuatable by said operating device prior to the actuation by the latter of the associated motion transmitting element, and lock releasing means in the 20 branch line.
- 25 7. In a railway switch, an automatically closing switch point, means for locking the same in open and closed positions, releasing means, a train controlled device in the main line for first unlocking and then throwing the switch, a train controlled device in the branch line adapted to throw the switch upon the passage of a train from the branch line to the main line and to hold the switch 30 open upon the passage of a train from the main line to the branch line, and train controlled devices in the branch line on opposite sides of said switch throwing device for unlocking the switch when the train approaches or leaves the main line.
- 35 8. In a railway switch, an automatically closing switch point, a point shifting element, means for locking the same in switch opening and closing positions, a train controlled switch throwing device in the main line, a releasing connection between said switch throwing device and the point shifting element, a train controlled device in the branch line, a lost-motion connection between the same and the point shifting element, and train controlled devices in the 40 branch line on opposite sides of said switch throwing device for unlocking the switch when the train approaches or leaves the main line.
- 45 9. In a railway switch, a switch throwing device comprising a revolute member having a spiral groove, in combination with an actuating member adapted to travel in said

groove, said groove being formed to effect 65 the switch actuating movement of the revolute member in the preliminary portion of the travel of the actuating member and to return said revolute member to normal position in the final portion of the travel of 70 said actuating member.

10. In a railway switch, an automatically closing switch point, a switch bar connected therewith, a locking device for holding the switch bar in switch opening and closing 75 positions, switch-throwing devices, motion transmitting connections between the same and the switch bar, each of said motion transmitting connections having a lost-motion element therein, means actuated by one 80 of said switch-throwing devices for releasing the locking device prior to the actuation by said switch-throwing device of the switch bar, and means for releasing the locking device prior and subsequent to the actuation of 85 the other switch-throwing device when a train approaches or leaves the main line.

11. In a railway switch, a self-closing switch point, a switch bar connected therewith, said bar comprising sections having a 90 lost-motion connection, a train-controlled switch-throwing device having a lost-motion connection with one of the sections of the switch bar, a locking device engageable with the other section of the switch bar for locking the switch bar in switch opening and closing positions, a connection between said locking device and the said switch-throwing device, said switch-throwing device being operable on the lost-motion take-up period 100 of its switch-throwing action to operate said connection to effect the release of the locking device, whereby the locking device will first be released and the bar then thrown to open the switch, a second train-controlled switch-throwing device connected with the second-named section of the switch bar, and lock 105 releasing devices arranged for actuation prior and subsequent to the actuation of said second switch-throwing device.

12. In a railway switch, an automatically closing switch point, a locking device for locking said switch point in switch opening and closing positions, a switch-throwing device having a lost-motion connection with the switch point and a controlling connection with the locking device, said switch-throwing device being operative to first release the locking device and take up the lost-motion and then to throw the switch, a second switch-throwing device also having a lost-motion connection with the switch point and operative on actuation to first take up the lost-motion and then throw the switch, and train controlled means for releasing the locking device upon the approach of a train in either direction toward said second switch-throwing device, said second switch- 110 115 120 125

throwing device being operative to hold the switch open during the passage of a train between the points named.

13. In a railway switch, an automatically closing switch point, a locking device for locking the switch point in switch opening and closing positions, a switch-throwing device having a lost-motion connection with the switch point and a controlling connection with the locking device, said switch-throwing device being operative on actuation to first release the locking device and take up the lost-motion and to then throw the switch, a second switch-throwing device comprising a laterally movable rail having a lost-motion connection with the switch point, train-controlled elements adjacent to and beyond the ends of the said rail, and a lock releasing device controlled thereby.
14. In a railway switch, an automatically closing switch point, a switch bar connected therewith, a spring projected locking device adapted to engage the switch bar to lock the switch point in open and closed positions, a member upon the switch bar having opposed cam surfaces, a switch-throwing device including a rock shaft, a cam carried by said shaft and movable between said cam surfaces to shift the switch bar in opposite directions, a lug carried by the rock shaft, and an element operated thereby for controlling said locking device.

15. In a railway switch, a switch throwing member, a switch point, a switch bar connected with the switch point and comprising sections coupled by a lost motion connection, a second switch throwing member having a lost motion connection with the switch point, and a lost motion throw connection between the switch bar and first-named switch throwing member.

16. In a railway switch, a switch point, means for normally holding the same closed, a shifting bar connected with the switch point and composed of sections having a

slip-joint connection, a revoluble switch throwing device in the main line, a cam operated thereby and having a lost motion connection with the shifting bar, a laterally movable switch shifting device in the branch line, means coupling the same to the switch point or shifting bar, said means including elements having a lost motion connection, a latch device for holding the switch point in closed and opened positions, and means controlled by the switch throwing devices for operating said latch device.

17. In a railway switch, a switch point, switch throwing devices in the main and branch lines, a shifting bar, a latch for locking said bar in switch opening and closing positions, a lost motion cam or eccentric connection between the switch bar and switch throwing device in the main line, means operated by said switch throwing device to retract the latch prior to shifting the shifting bar, transmission mechanism connecting the switch throwing device in the branch line with the switch point or shifting bar, said mechanism having lost motion means, and means arranged in the branch line for controlling the latch.

18. In a switch throwing device, a normally locked switch point, means in the main line for first unlocking the switch, then opening it and finally locking it in open position, and means arranged in the branch line for controlling the switch point in like manner and primarily releasing it for closure on the passage of a train from the main line to a branch line, said means operating under such conditions to hold the switch point open until the train fully enters the main line.

In testimony whereof I affix my signature in presence of two witnesses.

MARSHALL L. SHEPHERD.
